(57) **CLAIM**

The ornamental design for a free-standing kiosk, as shown and described.

DESCRIPTION

FIG. 1 is a front right perspective view of the free-standing kiosk of the instant invention;

FIG. 2 is a front view thereof;

FIG. 3 is a rear view thereof;

FIG. 4 is a right side view thereof, the left side view being a mirror image thereof; and,

FIG. 5 is a top view thereof.

The portions of the figures illustrated in broken lines are for illustrative purposes only and form no part of the claimed design.
